US00D559800S

(12) **United States Design Patent** (10) Patent No.: **US D559,800 S**
Neveu (45) Date of Patent: **** Jan. 15, 2008**

(54) **ELECTRICAL ENERGY CONTROL SWITCH**

(75) Inventor: **Stephane Neveu**, Strasbourg (FR)

(73) Assignees: **Legrand France**, Limoges (FR);
Legrand SNC, Limoges (FR)

(**) Term: **14 Years**

(21) Appl. No.: **29/269,756**

(22) Filed: **Dec. 8, 2006**

(30) **Foreign Application Priority Data**

Jun. 12, 2006 (EM) 000545603

(51) **LOC (8) Cl.** 13-03

(52) **U.S. Cl.** D13/174

(58) **Field of Classification Search** D13/158,
D13/160-164, 177, 184; 200/11 R, 16 B;
204/297; 205/118; D23/250-252; D8/310-312;
D14/217

See application file for complete search history.

(57) **CLAIM**

The ornamental design for an <<electrical energy control switch>>, as shown.

DESCRIPTION

FIG. 1 is a front elevational view thereof;

FIG. 2 is a left side elevational view thereof;

FIG. 3 is a right side elevational view thereof;

FIG. 4 is a top view thereof;

FIG. 5 is a bottom view thereof; and,

FIG. 6 is a perspective view.
